UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,991, dated October 26, 1880.

Application filed July 31, 1880. Term of patent 3½ years.

To all whom it may concern:

Be it known that I, EDUARD LEISSNER, of the city of New York, in the county and State of New York, have invented a new and original Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

The groundwork *a* of the paper is covered with zigzag stripes, each dotted or lightly striped, as shown. Over the background so

marked are laid the branches *b*, flowers *c*, and poppy-head-shaped buds *d*, all of which have undulating outlines, giving to the whole design an appearance resembling mediæval embroidery.

I claim—

1. The design for a wall-paper, consisting of the branches *b*, flowers *c*, and buds *d*, having undulating outlines, substantially as shown.

2. The design for a wall-paper, consisting of branches *b* and flowers *c* on zigzag-striped groundwork *a*, substantially as shown.

EDUARD LEISSNER.
